UNITED STATES PATENT OFFICE.

HERBERT G. IRWIN, OF FLOYDADA, TEXAS.

HEATING PRIMER.

Application filed June 15, 1920. Serial No. 389,217.

To all whom it may concern:

Be it known that I, HERBERT G. IRWIN, citizen of the United States, residing at Floydada, in the county of Floyd and State 5 of Texas, have invented certain new and useful Improvements in Heating Primers, of which the following is a specification.

This invention relates to a heating primer for starting cold internal combustion engines.

10 The invention provides a primer of this character in which an electric fuel heater is attached in combination with the vacuum tank of the fuel feed system and serves to heat an initial quantity of fuel for starting purposes, such fuel to be drawn into the intake manifold of the engine by the suction created when starting.

15 A further object of the invention is to provide a fuel heater which is electrically energized from the starting battery of a motor vehicle and is provided with a valve for regulating the outlet of the heated fuel going to the engine and at the same time controlling the connection of the primer with the fuel feed system.

20 I am aware that previous heating primers have been devised and patented, but the present invention differs in principle from previously known devices in that the fuel in the 25 primer is regulated by the quantity of fuel in the gravity feed compartment of the vacuum tank.

In the drawings:

30 Figure 1 is a side elevation of an internal combustion engine mounted in a motor vehicle and having the present invention applied thereto.

35 Figure 2 is a vertical longitudinal section through the switch and valve controlling 40 means.

Figure 3 is a transverse section on the line 3—3 of Figure 2.

45 Figure 4 is a longitudinal vertical section through the heating chamber.

Figure 5 is a similar section through the heating element.

50 Figure 6 is a section on the line 6—6 of Figure 5.

In detail:

55 The invention, as herein shown, is associated with an internal combustion engine A of a motor vehicle, the cowl B of the body thereof, the cowl board C, dash D, and the vacuum feed tank E mounted on the dash D. The intake manifold of the engine A is indicated at F and the carburetor at G.

The main fuel feed line 1 connects with the vacuum tank E as shown at 2 and said vacuum tank is vented by a suitable connection 3 in the usual manner. Adjacent the outlet 4 of the vacuum tank is a T 5 connected with the said vacuum tank outlet and with the fuel supply line 6 to the carburetor G. The additional branch 7 of the T 5 is connected with a short nipple 8 which is connected in turn with an elbow 9 of the primer cylinder 10. The upper end of the primer cylinder 10 carries a cap valve 11 which will be later described but one side of this cap valve is connected by a short length of tubing 12 with the opening 13 in the said vacuum tank E, while the other end is connected by a pipe 14 to the intake manifold F as indicated at 15. This arrangement forms the usual communication, under normal conditions, between the intake manifold and the vacuum tank for drawing the fuel through the main supply line 1, to the vacuum chamber of the vacuum tank.

20 However, the cap valve 11 is so constructed that communication may be established by means of a valve element 16 of the turning plug variety with the vacuum tank and the manifold or with the interior of the primer cylinder 10 and the manifold for withdrawing and feeding into the manifold the contents of the primer cylinder. The turning plug 16 is passaged as at 17 and is tapered to fit in the tapered bore of the valve cap 11 which is threaded onto the cylinder 10 as indicated at 18, the valve being held in place by the washer 19 and screw 20. At one end the valve being carries the operating arm 21 the valve carries the operating arm 21 held in place by a nut 22 and said arm is held in the proper position for establishing communication only between the vacuum tank and inlet manifold by a coil spring 23 having a hook 24 engaging a pin 25 carried by a lug 26 of a band 27 encircling the primer cylinder 10. The lower end of the primer cylinder 10 is closed by the cap 28 connecting with the elbow 9.

25 A tubular member 29 having a threaded end 30 screws into the passage in the cap valve 11 and is adapted to extend down into the primer chamber 10, when the primer is assembled.

30 This tubular member 29 carries a perforate end 30a which is surrounded by the insulating strips 31 notched as shown in Figure 4, and having the configuration, in trans-

verse section, shown in Figure 6. These parts are secured by metallic fusion at the bottom and held in place over the fused end of the tube 30 by the rivet 32. Members 33 hold the insulating strips at the top. Wrapped about the insulating strips, as shown in Figs. 4 and 5 is a heating element 34, the convolutions of which seat in notches 35 of the insulating member. One end of the heating element is connected to a binding post 36 which is insulated from the cap 10 by a suitable insulating bushing 37 and washers 38. The other end of the heating element is secured to the rivet 32 as indicated at 39. One terminal 40 of the electric circuit is connected to the binding post 36 and connection is made with the other end of the heating element by the usual ground connection to the engine.

It will be seen from the foregoing construction that if the primer cylinder 10 is located with respect to the vacuum tank as indicated in Fig. 1, the level of fuel in the primer cylinder 10 will be equal, in height, to the level of the fuel in the gravity chamber of the vacuum tank E. Also it will be apparent that if the heating coil or element 34 is energized by the closing of a suitable switch the result will be that the gasoline or other fuel within the primer cylinder 10 will become heated and partially vaporous so that the opening of the valve by turning the valve element 16 so that communication is established between the intake manifold 15 and the primer cylinder will result in a certain amount of vaporous and heated fluid fuel flowing to the intake manifold F. This will be particularly true when the engine is being cranked for starting as the suction on the intake manifold will then pull the fuel out of the primer cylinder 10.

Mounted in the cowl board C of the vehicle is a switch body 41 consisting of an insulation plug 42 surrounded by a casing 43 having a flange 44 by means of which the switch body is fastened to the cowl board C. The insulation plug 42 is cylindrically bored as at 45 and receives a contact bushing divided into halves 47 and 48 spaced from each other as shown so that there is no electrical contact between the two. Each of these bushing halves 47 and 48 is connected with its respective binding post 49 and 50 which are suitably connected with the wires leading to the heating element of the primer and battery. Mounted for reciprocation in the bore 45 of the insulating body 42 of the switch is a plug 51 which carries the contact member 52 having spring fingers 53 shaped as shown at 54 for engagement with the bushing halves 47 and 48 to complete the circuit thereacross. A spring 55 is confined between the flange head 56 of the plug 51 and the insulation body 42 and such plug 65 is held in place by a cap screw 57 slotted as

shown at 58 to accommodate a screw driver and also slotted to permit an operating element 59 to engage the plug for movement of the same. This operating element reciprocates in a passage formed parallel to the axis of the switch body and integral with the casing 43 as indicated at 60. The operating element is connected by a link 61 with the arm 21 for moving the valve plug 16 and said operating element carries an abutment 62 which engages with the insulation plug 51 for moving the spring fingers 53 to form a contact with the two bushing halves 47 and 48. The operating element or member 59 is notched as indicated at 63 to engage with the pin 64 to hold the switch plug in the connected position when desired.

In using the primer, the operator of the vehicle just as he is about to start the car pulls the operating member 59 out by grasping the ring 65 with the result that the heating coil in the primer cylinder is energized and an initial charge of heated and partially vaporized fuel is drawn into the intake manifold F on starting. This insures ease of starting even in the coldest weather and with low grades of fuel.

I claim:

1. In a primer for internal combustion engines, an electrically heated chamber, a valve forming a cap therefor, a heating element carried by said valve within the chamber, means for admitting fuel to the chamber at the end opposite the said valve to flow over the heating element, and means for energizing said heating element.
2. In a primer for internal combustion engines, a chamber, a cap closing the chamber at one end, a discharge pipe depending from the cap into the chamber and opening at its lower end into the chamber, a valve upon the cap controlling flow through said pipe, and a heating element carried by the pipe.
3. In a primer for internal combustion engines, a chamber, a cap closing the chamber at one end, a discharge pipe depending from the cap into the chamber, a valve upon the cap controlling flow through said pipe, a perforate member mounted upon the lower end of said pipe, insulating strips secured about said perforate member, and a heating element mounted upon said strips.
4. The combination with an internal combustion engine, a subsidiary vacuum fuel tank, and a suction pipe connecting the tank with the engine intake manifold whereby fuel will be drawn into the tank, of a fuel heating device fed from the tank and connected with said pipe whereby heated fuel may be drawn into said manifold through said pipe.
5. The combination with an internal combustion engine, a subsidiary vacuum fuel tank, and a suction pipe connecting the tank with the engine intake manifold whereby

fuel will be drawn into the tank, of a fuel heating device fed from the tank and connected with said pipe, and a valve for diverting suction from the tank to said device whereby heated fuel will be drawn into the manifold through said pipe.

6. The combination with an internal combustion engine, a subsidiary vacuum fuel tank, and a suction pipe connecting the 10 tank with the engine intake manifold whereby fuel will be drawn into the tank, of a fuel heating device fed from the tank and connected with said pipe, a valve for diverting suction from the tank to said device 15 whereby heated fuel will be drawn into the manifold through said pipe, and resilient means normally holding the valve in posi-

tion establishing communication between the manifold and tank.

7. The combination with an internal combustion engine, a subsidiary vacuum fuel tank, and a suction pipe connecting the tank with the engine intake manifold whereby fuel will be drawn into the tank, of a fuel heating device connected with the tank 20 whereby fuel will stand in said device at the level of the fuel in the tank, a connection between the device and said pipe, and a valve for diverting suction from the tank to said device whereby heated fuel will be 25 drawn into the manifold through said pipe.

In testimony whereof I affix my signature.

HERBERT G. IRWIN. [L.S.]
